UNITED STATES PATENT OFFICE.

ELIJAH MCCOY, OF YPSILANTI, MICHIGAN, ASSIGNOR TO SULLIVAN M. CUTCHEON AND EDWARD P. ALLEN, OF SAME PLACE.

IMPROVEMENT IN STEAM-LUBRICATORS.

Specification forming part of Letters Patent No. **146,697**, dated January 20, 1874; application filed June 11, 1873.

To all whom it may concern:

Be it known that I, ELIJAH McCoy, of the city of Ypsilanti, in the county of Washtenaw and State of Michigan, have invented certain new and useful Improvements in Lubricators; and I do hereby declare that the following is a full, clear, and exact description thereof, reference being had to the accompanying drawings and to the letters of reference marked thereon, which form a part of this specification.

My invention relates to that class of steam-cylinder lubricators in which there is a central tube in the oil-cup, with a valve at the upper end of said tube; and the nature of my invention consists in the construction and arrangement of the valve at the upper end of such central valve, as will be hereinafter more fully set forth.

In order to enable others skilled in the art to which my invention appertains to make and use the same, I will now proceed to describe its construction and operation, referring to the annexed drawing, which represents a vertical section of my improvement.

A represents the tube, which passes centrally up through the oil-cup. Within the up-

per end of this tube is placed a thimble-valve or regulator, B, confined in the tube by means of the screw-cap C, in the top of which is the valve-seat *a*. The thimble-valve B rests upon a shoulder, *b*, in the tube, and at the lower end of the tube are slots or perforations *d d*, for the admission of oil into the tube after the oil has passed over the top of the valve.

The top of the valve B may or may not be provided with a valley or crease for the passage of oil, as desired.

Having thus fully described my invention, what I claim as new, and desire to secure by Letters Patent, is—

The thimble-valve B, provided with slots or perforations *d d*, and resting upon a shoulder, *b*, in the tube A, in combination with said tube A and cap C, substantially as and for the purposes herein set forth.

In testimony that I claim the foregoing as my own I affix my signature in presence of two witnesses.

ELIJAH MCCOY.
